(57) **CLAIM**

The ornamental design for a rear combination lamp for automobile, as shown and described.

DESCRIPTION

FIG. 1 is a left-front, perspective view of a rear combination lamp for automobile of my new design;

FIG. 2 is a front view of my new design;

FIG. 3 is a rear view of my new design;

FIG. 4 is a top view of my new design;

FIG. 5 is a bottom view of my new design;

FIG. 6 is a left-side view of my new design; and,

FIG. 7 is a right-side view of my new design.

My design includes the mirror image of the embodiment depicted.
